UNITED STATES PATENT OFFICE.

THOMAS W. MILLER, OF ASHLAND, OHIO, ASSIGNOR TO THE FAULTLESS RUBBER COMPANY, OF ASHLAND, OHIO, A CORPORATION OF OHIO.

DESIGN FOR A SYRINGE-BAG.

46,790.

Specification for Design.

Patented Dec. 22, 1914.

Application filed September 3, 1914. Serial No. 860,118. Term of patent 14 years.

To all whom it may concern:

Be it known that I, THOMAS W. MILLER, a citizen of the United States, residing at Ashland, in the county of Ashland and State of Ohio, have invented a new, original, and ornamental Design for a Syringe-Bag, of which the following is a specification, reference being had to the accompanying drawing, forming part thereof.

Figure 1 is a perspective view of a syringe

bag, showing my new design. Fig. 2 is a cross sectional view of the same.

I claim:

The ornamental design for a syringe bag, as shown.

THOMAS W. MILLER.

Witnesses:

C. D. HUBLER,
W. H. BALCH.
